UNITED STATES PATENT OFFICE.

BENJAMIN WOLHAUPTER, OF NEW ROCHELLE, NEW YORK, ASSIGNOR TO THE RAIL JOINT COMPANY, OF NEW YORK, N. Y., A CORPORATION OF NEW YORK.

ABRASION UNIT FOR RAIL JOINTS.

Application filed November 17, 1922. Serial No. 601,600.

To all whom it may concern:

Be it known that I, BENJAMIN WOLHAUPTER, a citizen of the United States, residing at New Rochelle, in the county of Westchester and State of New York, have invented certain new and useful Improvements in Abrasion Units for Rail Joints, of which the following is a specification.

This invention relates to rail joints, and more particularly to an improved abrasion unit or wear filler having novel features of construction and design that render it of special utility in connection with standard types of joint bars having a wedge fit in the fishing spaces of the rails, thereby to compensate for the wear which is usually focused on the bearing faces of the bars at or near the rail ends.

A primary object of the invention is to provide a simple, practical and reliable unit functioning as a chafing guard or wear filler adapted to compensate for the wear usually imposed on the joint bars, thereby materially increasing the life of the joint. To that end the invention contemplates a novel sectional construction engaging the under-side of the rail head and the upper side of the base flange of the rail, and vertically yieldable or adjustable to permit of the splice bar properly drawing into the fishing space of the rail as wear occurs.

In the above connection the invention contemplates a special formation of the vertical web portion of the unit which adequately provides for the horizontal shifting or adjustment of the unit as a whole or the divided sections thereof individually, as well as providing for the diminution or contraction of the vertical height of the unit as the latter is moved into engagement with the converging faces of the rails defining the fishing spaces thereof.

A further object of the invention is to provide an abrasion unit designed and formed to permit of the ready replacement of any of the sections of the unit, or as previously indicated, the shifting of one of the parts thereof longitudinally in either direction independently of the other between the rail and the bar, thereby giving a wide range of manipulation for repair and adjustment.

With the above and other objects in view which will more readily appear as the nature of the invention is better understood,

the same consists in the novel construction, combination and arrangement of parts hereinafter more fully described, illustrated and claimed.

A preferred and practical embodiment of the drawings is shown in the accompanying drawings, in which:

Figure 1 is a perspective view illustrating one form of the invention.

Figure 2 is a bisected vertical sectional view of the construction shown in Figure 1.

Figure 3 is a perspective view illustrating a modification of the invention.

Figure 4 is a bisected vertical sectional view of the construction shown in Figure 3.

Figure 5 is a side elevation with the joint bar removed illustrating a still further modification of the invention, the dotted line in this figure indicating the ends of the joint bar to illustrate greater length of the abrasion unit which is a feature applying to all forms of the invention.

A distinctive feature of the invention is to provide a divided abrasion unit comprising relatively thin hard metal sections adapted to be positioned between the splice bar and the rails for receiving the wear usually imposed upon the head and foot portions of the bar by the chafing action imposed thereon by the movement of the rail under passing wheel loads. In that connection the invention contemplates the use of sections of minimum uniform thickness throughout, thereby providing a construction that may be easily rolled and at the same time utilizing a minimum amount of metal. Obviously, these general features may be embodied in various structural forms and therefore the drawings are only illustrative of certain practical structures available for use with standard joint bars.

Therefore, by reference to the accompanying drawings, it will be seen that it is proposed to provide a wear unit designated generally as A and consisting of the upper and lower sections B and C, the same being made of relatively thin hard metal and adapted to be used at the head and foot of the joint bar respectively to protect the latter from direct engagement with the rail.

As shown in Figures 1 and 2 the intermediate or web portion of the upper and lower sections B and C may be of special formation to provide an interlocking engagement with

the joint bolts E^1 , E^2 , E^3 and E^4 , whereby the entire unit may be held locked in the desired adjusted or set position and thereby prevent creeping of the parts under the action of the passing wheel loads. In this form the upper and lower sections B and C are of angular formation and the web portion W of the lower section C is cut away at the intermediate portion and at the ends 10 to provide upstanding locking walls or tongues D adapted to fit into suitable recesses or notches D' in the web or skirt portion W' of the upper section B, sufficient clearance being left at the ends of the 15 tongues D, as shown, to admit of adjustment. Thus, the upper and lower sections B and C are detachably interlocked so that one section may be removed or replaced independently of the other, and yet when the 20 units are assembled in the joint, they are effectively held against unauthorized creeping or shifting, but, of course, the whole unit is capable of being shifted longitudinally.

25 The tongue portions D of the lower section C are shown provided with suitable openings 1, 2, 3 and 4 for receiving the joint bolts. The openings 1 and 3 are adapted to receive the bolts E^1 and E^3 in the normal 30 installation of the unit, while the bolt holes 2 and 4 are provided for the purpose of permitting the longitudinal shifting of the unit to bring fresh unworn portions of the sections B and C into use. When the unit is 35 installed the bolts E^2 and E^4 will be positioned in the open spaces or clearances provided by the formation of the tongues D in the web of the section, and when the interlocked sections B and C are to be shifted 40 longitudinally the bolts E^1 and E^3 are withdrawn from the openings 1 and 3 thereby to permit the holes 2 and 4 to register with the bolts E^2 and E^4 , whereupon the bolts are replaced.

45 In order to adequately protect the head and foot of the joint bar from contact with the rails in all adjusted positions of the unit, it will of course be understood that the members B and C constituting the unit are 50 of greater length than the normal length of the joint bar.

A further embodiment of the invention is illustrated in Figures 3 and 4 of the drawings from which it will be observed that the 55 unit A' consists of the upper and lower sections B' and C', the web or skirt portions D² and D³ of which are provided with the notches F for receiving the locking plates G, preferably carried by the joint bolts E^1 , E^2 , E^3 and E^4 . The said notches F and matching locking plates G may be square, as shown in the drawing, or they may be obviously made hexagonal, round or any other suitable shape, and may be applied to one or 60 more, or all of the bolts as desired, the fun-

damental purpose being to provide an intermediate key for establishing an interlocking engagement between the upper and lower sections B and C.

One of the distinctive features of the type 70 of lock for the upper and lower sections B' and C' shown in Figures 3 and 4, is that it provides for readily shifting either the upper or lower section independently of the other, thereby making a construction where- 75 in the upper and lower sections of the unit may be adjusted longitudinally from time to time, as wear occurs, without the necessity of shifting the entire unit.

A further form of the invention, which 80 provides for a more minute longitudinal adjustment of the sections B' and C', either as a unit or independently of each other, is shown in Figure 5 of the drawings. In this embodiment the upper and lower sections B² and C² have the web portions D³ formed with serrations or teeth H for engaging 85 with similar serrations or teeth on the locking members G' carried by the bolts E¹, E², etc. Obviously, this type of construction 90 provides a wide range of longitudinal adjustment for either the upper or lower section of the unit, and at the same time the adjustment may be effected to a minute degree, thereby making it possible to more 95 fully utilize all of the available unworn portions of the sections.

Thus, it will be seen that in all forms herein described the web of the unit which 100 permits the vertical yielding thereof is utilized as the locking connection between the upper and lower metal sections.

From the foregoing it will be apparent that the novel and distinctive feature of the present invention is to provide an abrasion 105 unit or wear filler consisting of separable sections which may be adjusted simultaneously or independently to bring fresh unworn portions thereof into use; and may also be replaced independently to save the 110 least worn section for further use.

Without further description it is thought that the features and advantages of the invention will be readily apparent to those skilled in the art and it will of course be understood that changes in the form, proportion and minor details of construction may be resorted to without departing from the spirit of the invention or scope of the appended claims.

I claim:

1. In a rail joint, the combination with the joint bar and the rail ends, of an adjustable divided metal abrasion unit bridging the joint between the rail ends and comprising separate independently removable and replaceable wear sections.

2. In a rail joint, the combination with the joint bar and the rail ends, of a divided metal abrasion unit consisting of separate

upper and lower wear sections bridging the joint between the rail ends and having a relative longitudinal adjustment, and means between the two wear sections for effecting 5 an interlock therebetween.

3. In a rail joint, the combination with a joint bar and the rail ends, of a divided longitudinally adjustable metal abrasion unit of greater length than the joint bar.

10 4. In a rail joint, the combination with a rail joint and the rail ends of a divided metal abrasion unit comprising upper and lower wear sections, and means between said sections for effecting a relatively adjustable 15 interlock therebetween.

5. In a rail joint, the combination with the joint bar, rail ends, and joint bolts, of a divided metal abrasion unit consisting of upper and lower sections, and means inter- 20 locked with the joint bolts and with the sections thereby to hold said sections in position.

25 6. In a rail joint, the combination with the joint bar, rail ends, and joint bolts, of a divided metal abrasion unit consisting of upper and lower sections, and means car-

ried by the joint bolts and detachably interlocking with said sections.

7. In a rail joint, the combination with the joint bar, rail ends, and joint bolts, of a divided metal abrasion unit consisting of upper and lower sections, and means carried by the joint bolts and detachably interlocking with the webs of said sections to permit of independent adjustment and replace- 30 35 ment of said sections.

8. In a rail joint, the combination with the joint bar, rail ends and joint bolts, of a divided metal abrasion unit consisting of upper and lower sections adapted to be 40 positioned between the bar and the rail ends, the web portions of said sections being provided with notches, and means carried by the joint bolts adapted to detachably interlock with the said notches.

45 In testimony whereof I hereunto affix my signature in the presence of two witnesses.

BENJAMIN WOLHAUPTER.
